UNITED STATES PATENT OFFICE.

ALBERT RYS, OF ESSEN-ON-THE-RUHR, GERMANY, ASSIGNOR TO FRIED. KRUPP AKTIENGESELLSCHAFT, OF ESSEN-ON-THE-RUHR, GERMANY.

ARMOR-PIERCING SHELL.

1,383,012.

Specification of Letters Patent. Patented June 28, 1921.

Application filed December 3, 1920. Serial No. 428,078.

To all whom it may concern:

Be it known that I, ALBERT RYS, residing at Essen-on-the-Ruhr, Germany, a citizen of the German Republic, have invented a certain new and useful Improvement in an Armor-Piercing Shell, for which I have filed an application in Germany, Dec. 7, 1917, and of which the following is a specification.

This invention relates to armor-piercing shells which are provided with a cap and a hollow hood projecting beyond the cap. The object of the invention is to improve shells of this kind in such wise that the hood does not injure the effect of said cap.

On the drawing a construction of the subject matter of the invention is shown by way of example.

Figure 1 shows the point of the shell in elevation with the cap and the hood in section,

Fig. 2 shows the corresponding top view, partly in section on line 2—2 of Fig. 1.

The point of the shell A carries an obtuse cap B. On the cap B there is fixed by screw threads a thin-walled hood C, which has a form favorable to overcome the resistance of the air. Further, the hood C is provided with a number of perforations c^1 which are

arranged at equal distances around the entire periphery of the hood.

Experiments have demonstrated that under otherwise equal conditions (equal striking energy and equal angle of incidence for instance) capped projectiles the hood of which has the described perforations have a considerably increased effect especially when hitting the target at acute striking angles, with respect to capped shells the hood of which has no perforations.

Claims:

1. Armor-piercing shell having a cap and a hollow hood projecting beyond the said cap, said hollow hood being provided with perforations.
2. Armor-piercing shell having a cap and a hollow hood projecting beyond said cap, said hollow hood being provided with perforations, arranged at equal distances around the entire periphery of the hood.

The foregoing specification signed at Essen, Germany, this 17 day of July, 1920.

ALBERT RYS.

In presence of—

HANS GOTTMANN,
JOHANN DECKERS.
